TRIPPING MECHANISM

Eric A. Ericson, Plainville, Conn., assignor to General Electric Company, a New York corporation

Application August 26, 1953, Serial No. 376,676

7 Claims. (Cl. 200—116)

1

The present invention relates to improved tripping mechanisms and particularly to such mechanisms of improved sensitivity.

Overload tripping mechanisms are widely used in air circuit breakers of the type that may be manually opened and closed with a snap action and tripped automatically in response to an overload current independent of the position of the manual operating member. There has been some difficulty in obtaining the desired sensitivity in the tripping mechanism, that is, in obtaining the desired amount of tripping movement in response to a given overload condition. It is accordingly an important object of my invention to provide a new and improved tripping mechanism having increased sensitivity.

It is another object of my invention to provide an improved tripping mechanism utilizing the additive deflections of two overload responsive members to effect the tripping operation.

Further objects and advantages of my invention will become apparent as the following description proceeds, reference being had to the accompanying drawing, and its scope pointed out in the appended claims. In the drawing, Fig. 1 is an elevational view, with the cover removed, of a manually operable, current responsive tripped circuit breaker embodying my invention and shown in the closed circuit position; Fig. 2 is an elevational view of the same breaker shown in the tripped position with the manual operating member held in the closed position; Fig. 3 is a perspective view of a portion of the tripping mechanism showing the details of construction; Fig. 4 is an elevational view of a circuit breaker with a portion of the cover broken away showing a modification of my invention and with the parts shown in the closed circuit position of the breaker; Fig. 5 is a similar view of the same breaker showing the parts in the tripped position, the manual operating member being retained in the closed position and Fig. 6 is a perspective view showing the details of construction of the latch and tripping mechanism of the breaker shown in Figs. 4 and 5.

Referring now to the drawings, and particularly to Figs. 1, 2 and 3, I have shown my invention embodied in an air circuit breaker comprising an open-sided housing 1 formed of suitable molded plastic insulating material and having recesses therein for the reception and retention of an operating mechanism. The housing is provided with a metal top plate 2 having return bent end portions 3 which seat in slots (not shown) in the housing. Within the return bent end portions 3 are disposed threaded nuts 4

2

adapted to receive bolts (not shown) for mounting circuit breaker upon a panel or the like. The operating mechanism is adapted to be held in place in the housing 1 by a side cover plate 5 (not shown) which is adapted to be connected to the housing by means of rivets passing through holes 5 in the housing 1. The mounting nuts 4 are disclosed and claimed in my co-pending application, Serial No. 342,633, filed March 16, 1953, 10 and assigned to the same assignee as this application.

Within the molded casing 1 is disposed a manual and automatic operating mechanism for a pair of cooperating switch contacts 6 and 7. 15 The contact 6 is stationary and is mounted upon a terminal member 8 projecting from the bottom of the casing 1. The movable contact member 7 is mounted upon a movable switch member, shown as an L-shaped contact arm 9 pivotally 20 mounted at a point intermediate its ends upon a fixed pivot pin 10 carried by the casing 1. The contact arm 9 is movable from the closed circuit position, shown in Fig. 1, where the contacts 6 and 7 are in engagement to an open circuit position (not shown) where the contact member 9 engages a fixed stop 11 formed on the casing. A second terminal member 12 is seated in suitable positioning recesses in the housing 1 and projects from the bottom of the housing opposite 25 the terminal member 8.

The L-shaped movable contact arm 9 is manually and automatically movable between open and closed circuit positions by means of an automatically releasable toggle mechanism shown in 30 the drawings in closed and tripped positions. The actuating mechanism, shown at Fig. 1 in its closed position, comprises a releasable carrier member 13 pivotally mounted upon a fixed pivot 35 14 fixed in the casing 1, and a pair of toggle links 15 and 16 pivotally connected, respectively, to the upper ends of the carrier member 13 and the contact arm 9 by means of movable pivot pins 15a and 16a, respectively. The adjacent ends of 40 the toggle links are pivoted together at their knee by means of a movable pivot pin 17. The toggle link 16 is connected intermediate its ends to the pivot pin 16a, and thus includes a portion 16b extending beyond the pin 16a and engaging a compression spring 18, the other end of which is 45 fixedly seated in a suitable recess in the casing 1.

The releasable carrier member 13 has mounted thereon at its lower end a slidable latch member 13a, biased to an extended position with respect to the carrier 13 by a spring 13b disposed between the latch member 13a and a portion of the carrier member 13. The latch member 13a

normally engages a current responsive tripping member 19 including generally parallel thermo-deformable arms 19a and 19b. The member 19 is mounted in a suitable recess in the lower part of casing 1 and the arms 19a and 19b thereof are connected in series circuit relation between the terminal 12 and the movable contact 7 by means of flexible conductors 20 and 21. A piece of sheet insulating material 22 is interposed between the arms to prevent a short circuit therebetween.

As is best seen from Fig. 3 the ends of the arms 19a and 19b engage the latch 13a in the closed circuit position of the breaker. The latch 13a is provided with an inwardly projecting stop 13c which rests upon an extension 19c of the arm 19a. A continuation of the latch 13d engages the end of the bimetallic arm 19b to prevent the movement of the carrier member 13 in a counter-clockwise direction as long as the extension 13d is in engagement with the thermostatic arm. In order to prevent the latch member from short circuiting the bimetallic arms 19a and 19b, a rivet 23 of insulating material is interposed between the extension 19c and the stop 13c on the latch.

Both of the arms 19a and 19b are arranged with the high expansion sides facing one another so that the deflection of both arms tends to separate the arms upon heating. Movement of the upper arm 19a lifts the latch member 13a against the bias of the spring 13b tending to release the extension 13d of the latch from the end of the other bimetallic arm 19b. At the same time, the deflection of the arm 19b is downward tending to release it from the extension 13d so that the tripping operation is effected by the additive deflection of the two thermal elements. As indicated in the drawing, the end of the arm 19a is cut away or, in other words, the extension 19c is offset and the arm 13c of the latch is formed by bending up a portion of the latch so as to provide clearance for the counterclockwise movement of the latch as the breaker trips. As will be readily understood, the calibration of the device may be controlled by suitable adjustment of the calibrating screw 24 carried by a supporting plate 25 to which the fixed ends of the bimetallic arms 19a and 19b are welded.

The manual operation of the circuit breaker is accomplished by means of the plunger 26 which is provided at its lower end with a link 27 connected to the knee pivot 17. The plunger is suitably shaped to engage the upper end of a cylindrical flange 28 in the casing to provide a stop for the operating mechanism.

The operation of the illustrated embodiment of my invention is briefly as follows: With the parts in the closed circuit position as illustrated in Fig. 1 and with the operating plunger 26 held in a depressed or closed position, the parts are biased to move to the position shown in Fig. 2 by the spring 18 and are retained in the position shown in Fig. 1 by means of the latching member 13a. Upon an occurrence of an overload of sufficient magnitude, bimetallic arms 19a and 19b both tend to deflect outwardly, that is to separate. The upper arm 19a lifts the latch member 13a against the bias of the spring 13b and at the same time the arm 19b moves downwardly in a direction to release the extension 13d of the latch member. Both of these movements tend to release the mechanism which upon release moves under the action of the spring 18 to the position shown in Fig. 2.

If the plunger 26 is now released, the spring 75

18 tends to lift the knee pivot 17 and return the operating plunger 26 to an upward or open position and at the same time to collapse the toggle upwardly and rotate the carrier member 13 in a clockwise direction until it is clear of the end of the thermal element at which time the breaker may be closed by pressing plunger 26 (provided the bimetallic arms have cooled sufficiently).

The particular mechanism for operating the breaker apart from the improved thermal trip described above is not a part of the present invention but is described and claimed in my co-pending joint application with Raymond N. Rowe, Serial No. 331,558, filed January 16, 1953, 15 now Patent No. 2,673,267 dated March 23, 1954, and assigned to the assignee of this application.

In Figs. 4, 5 and 6 I have shown a modification of my invention in which a movable latch member is carried by a stationary part of the switch 20 rather than by the movable carrier member 13 as described in connection with Figs. 1-3 inclusive. The breaker is in general of the same construction as that shown in Figs. 1-3 and the same reference numerals will be applied to corresponding parts. As illustrated in Figs. 4-6 the carrier member 13' is provided with an integral latching extension 13c for engaging, in the closed circuit position of the breaker shown in Fig. 4, the upper end of a latch member 28 which is mounted for both pivotal and vertical sliding movement in the slots 29 formed in the spaced side walls of the insulating casing. The thermal tripping member 19' includes a pair of spaced bimetallic arms 30 and 31 in general similar to the arms 19a and 19b but in this modification, there is no lateral offset on either arm. The upper arm 30 engages a lateral extension 28a on the latch member 28 and the lower arm 31 engages the stop 28b formed by bending a portion of the latch member over so that it extends perpendicularly from one face of the latch. The latch is biased upwardly in the slots 29 by means of a compression spring 32. As before, it is necessary to insulate at least one of the arms from the latch and a rivet 33 of insulating material is interposed between the arm 31 and the stop 28b for that purpose.

As will be readily apparent to those skilled in the art, the arms 30 and 31 of the thermal mechanism both deflect in a direction to separate the arms upon an occurrence of an overload. Movement of the arm 31 in a downward direction tends to move the latch downwardly in the slots 29 against the bias of the spring 32 and at the same time the arm 30 deflects upwardly tending to disengage it from the lateral extension 28a. Both of the movements, therefore, tend to cause release of the latching member which upon release tilts in a clockwise direction as illustrated in the drawing to release the latching tip 13c of the carrier member 13'. It will be understood that in other respects the mechanism of the modification shown in Figs. 4-6 operates in the same manner as that described in connection with Figs. 1-3 inclusive.

It is inherent in the thermal tripping mechanisms described above that magnetic forces due to large overload currents also tend to cause tripping of the breaker. Since the bimetallic arms 19a and 19b or 30 and 31 lie in closely spaced relation and conduct current in opposite directions, the magnetic forces tend to separate them. In this manner, the thermal tripping action is accelerated by the magnetic action when the overload is great.

While in the specific embodiments of my invention illustrated the overload responsive elements are thermally actuated it is apparent that the broader aspects of the invention including the utilization of the additive deflections of a pair of overload responsive members may be carried out, for example, with magnetically actuated overload members.

While there has been shown and described a particular embodiment of the invention, it will be obvious to those skilled in the art that changes and modifications may be made without departing from the invention, and that it is intended by the appended claims to cover all such changes and modifications as fall within the true spirit and scope of the invention.

What I claim as new and desire to secure by Letters Patent of the United States is:

1. An overload trip for a latch releasable mechanism including a biased member, a latch member for restraining said biased member and biased to one position, a pair of overload actuated members, one of said overload actuated members providing a stop for said latch member and movable upon the occurrence of an overload in a direction to release said latch and the other of said overload actuated members engaging said latch and movable in response to an overload to move said latch away from said one position whereby the movement of both said overload actuated members tends to release said biased member.

2. A thermal trip for a latch releasable mechanism including a biased member, a latch member for restraining said biased member and biased to one position, a pair of bimetallic members, one of said bimetallic members providing a stop for said latch member and movable upon an increase in temperature thereof in a direction to release said latch and the other of said bimetallic members engaging said latch and movable in response to a rise in temperature thereof to move said latch away from said one position whereby the movement of both said bimetallic elements upon a rise in temperature thereof tends to release said biased member.

3. A thermal trip for a latch releasable mechanism including a biased member, a latch member for restraining said biased member and biased to one position, a pair of longitudinally extending bimetallic members, one of said bimetallic members including means providing a stop for said latch member and movable upon an increase in temperature thereof in a direction to release said latch from said stop and the other of said bimetallic members engaging said latch and movable in response to a rise in temperature thereof to move said latch away from said one position whereby the movement of both said bimetallic elements upon a rise in temperature thereof tends to release said biased member.

4. A thermal trip for a latch releasable mechanism including a biased member, a latch member slidably mounted on said biased member for restraining said biased member, a pair of longitudinally extending bimetallic members, one of said bimetallic members providing a stop for said latch member and movable upon an increase in temperature thereof in a direction to release said latch and the other of said bimetallic members engaging said latch and movable in response to a rise in temperature thereof to move said latch in a direction to release said latch from said first bimetallic member whereby the movement of both said bimetallic elements upon a rise

in temperature thereof tends to release said biased member.

5. A thermal trip for a latch releasable mechanism including a biased member comprising a latch member for restraining said member and biased to one position, a pair of longitudinally extending bimetallic members supported in parallel and closely spaced relation and electrically connected together at one end, means connecting said bimetallic elements in a circuit to be protected, one of said bimetallic elements providing a stop for restraining said latch member and movable upon an increase in temperature thereof to release said latch member, the other of said bimetallic elements engaging said latch member and movable upon an increase in temperature thereof in a direction to move said latch member from said one position against said bias and in a direction opposite to the direction of movement of said first mentioned bimetallic element whereby the relative movement between said latch member and said first mentioned bimetallic element is the sum of the movement of said bimetallic elements.

6. A thermal trip for a latch releasable mechanism including a biased member comprising a latch member for restraining said biased member and biased to one position, a pair of current responsive thermal elements, means connecting said thermal elements in a circuit to be protected by said mechanism, one of said thermal elements providing a stop for restraining said latch member and movable upon an increase in temperature thereof to release said latch member, the other of said thermal elements engaging said latch member and movable upon an increase in temperature thereof in a direction to move said latch member from said one position against said bias and in a direction opposite to the direction of movement of said first mentioned thermal element whereby the relative movement between said latch member and said first mentioned thermal element is the sum of the movement of said thermal elements.

7. A thermal trip for a latch releasable mechanism including a biased member comprising a latch member for restraining said biased member, said latch member being supported for pivotal and reciprocating movement and biased to one position, a pair of longitudinally extending bimetallic members supported in parallel and closely spaced relation and electrically connected together at one end, means connecting said bimetallic elements in series in a circuit to be protected, one of said bimetallic elements providing a stop for restraining said latch member and movable upon an increase in temperature thereof to release said latch member, the other of said bimetallic elements engaging said latch member and movable upon an increase in temperature thereof in a direction to move said latch member from said one position against said bias and in a direction opposite to the direction of movement of said first mentioned bimetallic element whereby the relative movement between said latch member and said first mentioned bimetallic element is the sum of the movement of said bimetallic elements.
